UNITED STATES PATENT OFFICE.

EDWARD BARRS, OF LONDON, ENGLAND.

RABBLE FOR LOW-TEMPERATURE COAL-DISTILLATION PURPOSES.

Application filed December 19, 1921. Serial No. 523,456.

To all whom it may concern:

Be it known that I, EDWARD BARRS, a subject of the King of England, residing at Gray's Inn, London, England, have invented certain new and useful Improvements in Rabbles for Low-Temperature Coal-Distillation Purposes, of which the following is a specification.

This invention is for improvements in or 10 relating to rabbles for low temperature coal-distillation purposes or other purposes where a like movement of the material is required, and has for its object to provide a rabble of the type comprising a grid or 15 a plurality of grids disposed one behind the other, and arranged to be reciprocated along or over the furnace-chamber floor in such manner as to feed the material in the furnace-chamber forward and also turn it. 20 Rabbles arranged in this manner have usually been moved forward along the bed of the chamber, then raised vertically out of the material and carried back above the same, to be again dropped into it, and the 25 grids of the rabble have sometimes been sloped with a view to giving a turning movement to the material, but such arrangements have not been satisfactory.

For feeding material along the floor of 30 a chamber according to this invention, there is combined with a rabble of the type described, means for causing it to travel in a path which is both upwardly and forwardly directed near the limit of its forward movement for the purpose of causing 35 the material, as it is moved forward, to roll upon itself and pile in heaps of approximately V-shaped across-section.

The means for guiding the rabble preferably take the form of laterally disposed 40 rollers on the rabble which run upon upper and lower tracks connected by ramps at points traversed by the rollers towards the end of the forward movement, provided 45 with means whereby the rollers can pass from the tops of the ramps to the upper tracks during backward travel, and with means whereby the rollers can pass at the end of their rearward movement to the lower tracks.

The means for supporting the rollers during their passage from the tops of the ramps to the upper tracks may take the form of shunt-plates moved into position (for example lengthwise) to bridge the gaps in the 50 upper tracks through which the rollers rise

in ascending the ramps and moved back to clear the said gaps prior to the next traversing of the ramps by the rollers.

In the accompanying drawings which illustrate one method of carrying out this invention:—

Figure 1 is a vertical central section through the chamber in which the material is to be treated showing the rabble in elevation therein; the central portion of the chamber is broken away.

Figure 2 is a side elevation of the rear end of the rabble on a larger scale than that of Figure 1.

Figure 3 is a plan of the rear end of the rabble.

Figure 4 is a diagrammatic view of part of the shunt-plate in perspective.

Figure 5 is a corresponding diagrammatic view of one of the guide-plates in perspective.

Figure 6 is a perspective view of part of the shunt-plate in the form in which it is used.

Figure 7 is a perspective view of part of the guide-plate in the form in which it is used.

Figure 8 is a central vertical section through part of a chamber and rabble constructed according to a modified method of carrying out this invention, and

Figure 9 is a transverse section of part of the chamber and rabble shown in Figure 8.

Like reference letters indicate like parts throughout the drawings.

The furnace chamber A may be of any convenient construction, that shown being provided with heating-conduits A¹ which are fed with hot fluid from any convenient source and discharge into a chamber A² at the rear of the furnace-chamber. The heating conduits referred to are described and claimed in my application Serial No. 523,457, filed December 19, 1921. The apparatus arranged as shown, may be used for low temperature distillation of coal. A hopper B is provided at the rear end and coal fed in thereby will spread out on the bottom of the chamber somewhat as shown at B¹. The rabble C comprises a frame having two longitudinal members suitably braced together and is supported by laterally disposed rollers C¹ mounted outside the said longitudinal members.

Along each side of the chamber in which the rabble operates is a longitudinally dis-

posed guide-member D, Figures 1, 5 and 7, upon which the guide-rollers C¹ run, and as both guide-members are alike one only need be described in detail, and indeed, the drawings only show that one which faces the observer in the sectional view of the apparatus shown in Figure 1. The member D is approximately in the form of an H-girder having upper and lower flanges on both 10 sides, but the flanges on the inner side, that is the side towards the chamber are those which alone concern the present invention; these flanges are indicated at D¹ and D² respectively. The rollers C¹ run on these 15 flanges and gaps D³ and D⁴ are provided in the upper flange to permit the rollers to pass from the lower to the upper flange. Rising from the lower flange to the upper flange in each gap D³ is a ramp E up which 20 the rollers can run and this ramp is extended above the level of the upper flange D¹.

Sliding, one on each member D, is a shunt-plate F, Figures 1, 4 and 6. This may be 25 a member of L-shaped cross-section having lateral projections or lugs F¹ and F² on that face from which the bottom web does not extend. In Figures 4 and 5 the parts are shown diagrammatically so as to dispense 30 with certain steps in the parts F¹, F² and the gaps D³, D⁴ of the guide-plate which make the construction more difficult to follow in a drawing, but the actual construction used is shown in Figures 6 and 7 and 35 can be recognised by the like letters. The projections F¹ lie flush with the bottom of the shunt-plate and when the shunt-plate rests on the guide-plate at the extreme limit of its movement to the right, as viewed in 40 Figures 4 and 5, the parts F¹ bridge the gaps D³, the undercut forward end of each bridge-piece lying over the upper portion of the corresponding ramp E. The rear end of each bridge-piece F¹ is bevelled on the 45 upper side and a space is left between this end and the projection or stop F² sufficient to accommodate one of the rollers C.

The rabble carries on its underside a number of scrapers C² which depend from the 50 rabble, each scraper being perforated to constitute a grid, as shown at C³ Figure 2, and being supported at the back by one or more webs C⁴. The rabble is reciprocated by any convenient form of engine having 55 operative connection with it by means of the connecting-rod indicated at G, Figure 1.

The operation of the rabble is as follows:—

When it is in the position shown in the 60 drawings, with the rollers on top of the flat portions E¹ extending forwardly from the ramps E, the rabble is at the full limit of its forward movement and at the highest point it reaches. The grids C² then 65 lie clear of the coal-heaps B², Figure 1,

and the backward movement is about to commence. As the rabble travels back the shunt-plates F remain stationary during the passage of the rollers along the flat portions E¹ and over the bridge-pieces F¹ of 70 the shunt-plates. The rollers thus pass over the gaps D³ and drop down the bevelled ends of the parts F¹ on to the upper flanges D¹ of the guide-plates. The shunt-plates are now relieved from the load of the rabble 75 and the rollers C come against the stops F² on the shunt-plates so that the shunt-plates will now move backward with the rollers until the rollers come over the gap D⁴ when the rabble will drop until the rollers are 80 arrested by the bottom flanges D². The grids now lie in front of the heaps B² of the coal and will thus move them forward as the rabble advances, with the rollers running on the bottom flanges D². When the 85 rollers strike the ramps E they travel up the same and in so doing the grids give an upward and forward wiping action over the face of the coal-heaps which causes the coal to roll upon itself, whereby in its 90 course through the chamber all parts are equally exposed to heat. The gaps D³ are open as the shunt-plate remains in the position it was moved to by the backward travel 95 of the rabble and so the rollers C¹ can pass freely up the ramps E and on to the level portions E¹. The projections F², however, overhang the level portions E¹ and thus the rollers travelling along these parts will strike against the back ends of the stops F² and cause the shunt-plate to move forward. It will be observed that during this 100 forward movement of the shunt-plates the load of the rabble is not on the shunt-plates and therefore they can move freely. When the rabble has reached the end of its forward movement the parts are again in the starting position and the operation just described is repeated.

To prevent possible undue displacement of the shunt-plates endwise, each plate has a gap H in the bottom web which co-operates with a stop H¹ on the top of the guide-plate.

To rake the coal forward from the heap 115 B¹ the rabble is provided with three sets of raking-fingers, J, J¹ and J² respectively which are placed successively further to the rear of the rabble and at higher levels. As 120 shown in Figures 2 and 3, the fingers J¹ are further to the rear and higher than the fingers J, whilst the fingers J² are similarly placed with respect to the fingers J¹. These fingers drop into the heap B¹ when the rabble drops and rake it forward for engagement on the next rearward movement by the rearmost grid C². To prevent coal from packing in the hopper B, two pack-breakers J³ which have hook-like ends J⁴ are also 125 mounted on the rear of the rabble and ex- 130

tend further back than the raking-fingers so that they enter the coal within the mouth of the hopper as the rabble travels backward and will thus disturb it when the rabble drops and also when it begins its forward movement.

In case the rabble drops too heavily it may be counter-balanced and for this purpose it is shown as provided with wire-cables K, Figures 8 and 9, guided over pulleys K¹ and provided with counter-balancing weights K². The cables pass through stuffing-boxes indicated diagrammatically at L in the roof of the chamber so that the counter-balancing weights can be arranged outside the furnace-chamber. The counter-balancing weights would be arranged in pairs along the length of the rabble, as many pairs being employed as found desirable.

The top of the furnace-chamber is provided with a series of upwardly extended collecting-chambers M, each with an outlet M¹ for gases driven off by the operation of heat upon the material under treatment, and where the nature of the gases changes as the material travels along the furnace it may be desirable to curtain off one collecting-chamber and its corresponding portion 30 of the furnace-chamber from the next collecting-chamber and its corresponding portion of the furnace-chamber. For this purpose a double series of downwardly-directed steam-nozzles N, N¹ may be provided at the 35 point where one collecting-chamber ends and the next begins, so that a double curtain of steam may be maintained across the furnace-chamber at these points, and the space between one row of steam-nozzles and its 40 companion row is such that when the grid passing beneath it breaks through one row the other row is maintaining the required curtain.

I claim:

1. The combination with a reciprocatory rabble comprising a frame, scrapers depending therefrom, and a plurality of supporting rollers mounted laterally on the frame, of a pair of fixed upper tracks for the rollers, a pair of fixed lower tracks for the rollers, which upper tracks are so shaped and each so arranged in relation to its corresponding lower track that at a point traversed by the rollers towards the end of their rearward movement the rollers can travel off their upper tracks on to the lower, a plurality of ramps, one for each roller, each rising from a lower track towards the corresponding upper track at a point traversed by a roller 50 towards the end of its forward movement, and shunt-plates, one for each upper track, arranged to connect the top of each ramp with its allotted upper track for guiding the rollers on to the upper tracks during their 55 rearward movement, and slidably into a position

wherein the ramps are left unobstructed for the upward travel of the rollers on to them.

2. The combination with a reciprocatory rabble comprising a frame, scrapers depending therefrom, and a plurality of rollers mounted laterally on the frame, of a pair of fixed upper tracks for the rollers, a pair of fixed lower tracks for the rollers, which upper tracks are each so shaped and each so arranged in relation to its corresponding lower track that at a point traversed by the rollers towards the end of their rearward movement the rollers can travel off the upper tracks on to the lower, a plurality of ramps, one for each roller, each rising from a lower track towards the corresponding upper track at a point traversed by a roller towards the end of its forward movement, and two shunt-plates, one for each upper track, arranged to be automatically moved endwise by said rollers into its two end positions, in one of which positions the shunt-plates connect the top of each ramp with its allotted upper track, and in the other end position leave the ramps unobstructed for the upward travel of the rollers on them, lost motion being provided between the rearward and forward movement of the shunt-plates.

3. The combination with a reciprocatory rabble comprising a frame, scrapers depending therefrom, and a plurality of rollers mounted laterally on the frame, of a pair of upper tracks for the rollers, a pair of lower tracks for the rollers, which upper tracks are each separated by gaps into sections, some of which gaps are so arranged that the rollers can travel off the upper tracks on to the lower at the end of their rearward movement, a plurality of ramps, one for each roller, each rising from a lower track towards the forward end of a gap in the corresponding upper track at a point traversed by a roller towards the end of its forward movement, and slidable shunt-plates, one for each upper track, having lugs each arranged in one end position of the shunt-plates, to bridge a gap at the top of a ramp, and movable with the shunt-plates into the other end position wherein the ramps are left unobstructed for the upward travel of the rollers on them.

4. The combination with a reciprocatory rabble comprising a frame, scrapers depending therefrom, and a plurality of rollers mounted laterally on the frame, of a pair of upper tracks for the rollers, a pair of lower tracks for the rollers, which upper tracks are each separated by gaps into sections, some of which gaps are so arranged that at a point traversed by the rollers towards the end of their rearward movement the rollers can pass through these gaps off the upper tracks and on to the lower, a plurality of

ramps, one for each roller, each rising from a lower track towards the forward end of a gap in the corresponding upper track at a point traversed by a roller towards the end 5 of its forward movement, and shunt-plates, one for each upper track, having stops arranged to coat with, and be driven by the rabble and drive the shunt-plates into two end positions, lost motion being provided between 10 the backward and forward movements of the plates, said shunt-plates having lugs each arranged, in one end position of the shunt-plates, to bridge a gap at the top of a ramp, and movable with the shunt- 15 plates into the other end position wherein the ramps are left unobstructed for the upper travel of the rollers on them.

5. The combination with a reciprocatory rabble comprising a frame, scrapers depending therefrom, and a plurality of rollers mounted laterally on the frame, of a pair of upper tracks and a pair of lower tracks for the rollers, which upper tracks are each so shaped and each so arranged in relation 20 to its corresponding lower track that at a point traversed by the rollers towards the end of their rearward movement the rollers can travel off the upper tracks on to the lower, a plurality of ramps, one for each 25 roller, each rising from a lower track towards the corresponding upper track at a point traversed by a roller towards the end of its forward movement, and two shunt-plates, one for each upper track, slideable 30 endwise on the upper tracks, said ramps extending each above one of said shunt-plates, which shunt-plates have each a stop arranged to coat with the rabble for automatically moving the shunt-plates into two 35 end positions, in one of which positions the shunt-plates connect the top of each ramp with its allotted upper track, and in the other end position leave the ramps unobstructed for the upward travel of the rollers 40 on them, the said stops being so disposed in relation to the parts of the rabble, with which they coat that lost motion is provided between the rearward and forward movements of the shunt-plates.

50 6. The combination with a reciprocatory rabble comprising a frame, scrapers depending therefrom, and a plurality of rollers mounted laterally on the frame, of a pair of upper tracks and a pair of lower tracks for the rollers, which upper tracks are each separated by gaps into sections, some of 55 which gaps are so arranged that at a point traversed by the rollers towards the end of their rearward movement the rollers can 60 pass through these gaps off the upper tracks and on to the lower, a plurality of ramps, one for each roller, each rising from a lower track towards the forward end of a gap in the corresponding upper track at a point 65 traversed by a roller towards the end of its

forward movement, and shunt-plates, one for each upper track, having stops arranged to coat with and be driven by said rollers and drive the shunt-plates into two end positions, lost motion being provided between 70 the backward and forward movements of the plates, said shunt-plates having lugs each arranged, in one end position of the shunt-plates, to bridge a gap at the top of a ramp, and movable with the shunt-plates 75 into the other end position wherein the ramps are left unobstructed for the upper travel of the rollers on them, each stop on a shunt-plate being spaced away rearwardly from the adjacent end of a lug on the same 80 shunt-plate so far that the rollers with which the stops coat are off the said lugs when the rearward movement of the shunt-plates commences.

7. The combination with a reciprocatory 85 rabble comprising a frame, a plurality of transverse scrapers depending one behind another therefrom, a plurality of supporting rollers mounted laterally on the frame, and a plurality of downwardly directed 90 raking fingers mounted on the rear end of the frame and arranged at different levels, of a pair of fixed upper tracks for the rollers, a pair of fixed lower tracks for the rollers, which upper tracks are so shaped 95 and each so arranged in relation to its corresponding lower track that at a point traversed by the rollers towards the end of their rearward movement the rollers can travel off their upper tracks on to the lower, a plurality of ramps, one for each roller, each rising from a lower track towards the corresponding upper track at a point traversed by a roller towards the end of its forward movement, and shunt-plates, one for each upper track, arranged to connect the top of each ramp with its allotted upper track for guiding the rollers on to the upper tracks during their rearward movement, and slideable 100 into a position wherein the ramps are left unobstructed for the upward travel of the rollers on to them.

8. The combination with a reciprocatory 105 rabble comprising a frame, a plurality of transverse scrapers depending one behind 110 another therefrom, a plurality of supporting rollers mounted laterally on the frame, and a plurality of downwardly directed raking fingers mounted on the rear end of the frame and arranged in a plurality of series located successively further to the rear beyond the adjacent end of the frame and at successively higher levels, of a pair of fixed upper tracks for the rollers, a pair of fixed lower tracks for the rollers, which upper tracks 115 are so shaped and each so arranged in relation to its corresponding lower tracks that at a point traversed by the rollers towards the end of their rearward movements the rollers can travel off their upper tracks on 120 125

to the lower, a plurality of ramps, one for each roller, each rising from a lower track towards the corresponding upper track at a point traversed by a roller towards the 5 end of its forward movement, and shunt-plates, one for each upper track, arranged to connect the top of each ramp with its allotted upper track for guiding the rollers on to the upper tracks during their rear- 10 ward movement, and slidably into a position wherein the ramps are left unobstructed for the upward travel of the rollers on to them.

9. A rabble comprising in combination a supporting frame having laterally-disposed 15 rollers for running on tracks, a plurality of transverse scrapers depending one behind another from said frame, a plurality of downwardly-directed raking-fingers mounted on the rear end of the frame and arranged 20 at different levels, and a pack-breaker mounted on the rear of the frame and extending to the rear further than said raking-fingers.

10. A rabble comprising in combination 25 a supporting frame having rollers for running on tracks, and a plurality of transverse scrapers depending one behind another from said frame, a plurality of downwardly-directed raking-fingers mounted on the 30 rear end of the frame and arranged at different levels, and a plurality of upwardly directed hooked pack-breakers mounted on the rear of the frame and extending between said raking-fingers further to the rear than 35 the said fingers.

11. The combination of a chamber, a reciprocal rabble therein comprising a frame, scrapers depending from the latter, and a plurality of supporting rollers mounted laterally on the frame; a pair of upper 40 tracks and a pair of lower tracks in said chamber for the rollers, which upper tracks are each so shaped and each so arranged

in relation to its corresponding lower track that at a point traversed by the rollers towards the end of their movement in one direction, the rollers can travel off the upper track on to the lower, a plurality of ramps, one for each roller, each rising from a lower track towards the corresponding upper 50 track at a point traversed by a roller towards the end of its forward movement, and shunt-plates, one for each upper track, arranged to connect the top of each ramp with its allotted upper track for guiding 55 the rollers on to the upper track during their rearward movement, and movable into a position wherein the ramps are left unobstructed for the upward travel of the rollers on them, pairs of cables extending 60 through the walls of the chamber and having their inner ends attached to two opposite sides of the rabble counterweights attached to the outer ends of the cables, and pulleys on the walls of the chamber carrying 65 said cables.

12. The combination with the running roller of a reciprocating rabble, of a fixed upper and a fixed lower track therefor, which upper track is so arranged in spaced 70 relation to the lower that at a point traversed by the roller towards the end of its movement in the one direction the roller can fall through space off the upper track on to the lower, a ramp rising from the lower 75 track towards the upper at a point traversed by the roller towards the end of its movement in the other direction, and an endwise slidable shunting-member connecting the top of the ramp with the upper track for 80 guiding the roller on to the latter during its movement in the first said direction.

In testimony whereof I affix my signature.

EDWARD BARRS.
